UNITED STATES PATENT OFFICE

JEAN GALLAY, OF GENEVA, SWITZERLAND.

ELECTRIC SEARCH-LAMP FOR AUTOMOBILES.

1,083,530.

Specification of Letters Patent.

Patented Jan. 6, 1914.

Application filed January 6, 1913. Serial No. 740,332.

To all whom it may concern:

Be it known that I, JEAN GALLAY, manufacturer, citizen of Switzerland, residing at 66 Route de Frontenex, Geneva, Switzerland, have invented certain new and useful Improvements in Electric Search-Lamps for Automobiles; and I do hereby declare the following to be a full, clear, and exact description of the invention, such as will enable others skilled in the art to which it app pertains to make and use the same, reference being had to the accompanying drawing, and to figures of reference marked thereon, which form a part of this specification.

The present invention relates to electric search lamps for automobiles in which the active surface of the reflector is hermetically isolated from the surrounding space, whereby the deposit of dust and steam mist upon such surface is entirely avoided. Moreover, the lamp may be adjusted in the focal plane of the reflector without having to open the lantern for the purpose, which affords the further advantage of no exterior projection being presented which might hamper cleaning operations.

The accompanying drawing illustrates a suitable manner of carrying out the object of the invention Figure 1, being a longitudinal section and Fig. 2 a section on line $x-y$ of Fig. 1.

The reflector a of the lamp is of parabolic form; at its forward part it terminates in a rim a' forming a seat to receive the glass b and at the rear in a ring a'' . In a groove formed in the rim a' is situated a rubber washer c against which the glass b is pressed by a front ring d screwing on to the rim a' . This ring is in section of mushroom form and its body constitutes a screw serving with its interior edge to bind the glass b against the india rubber packing while its outer edge embraces the casing e of the lamp when the reflector is in position. The latter is open at the rear for the passage of the lamp l fitted in the plug f which screws into the ring a'' of the reflector and bears against the rim e' of the casing e , so that in screwing home said plug, the reflector a is drawn to the back of the casing and the front ring d forced against the latter. The opening in the reflector for the passage of the lamp is closed by a movable back g which can slide on the ring f' , at the front of plug f , and which is held against the reflector a by the helical spring h bearing against the bottom

of the plug f . The ring l' of the lamp is seated in a ring g' secured to the rear of the movable ring g and is in one with the screw threaded tube m which passes through the plug f . This tube is hollow; it affords passages for the electric leads and carries a nut n with stops, the nut bearing exteriorly against the plug f , while a spring o tends to force the ring and its tube m toward the interior. By this arrangement, by turning the nut in one or other direction the lamp can be brought into the focal plane of the reflector.

The lamp is fixed on a fork entering into sockets q which are soldered to the interior of the casing e (Fig. 2). By this method of suspension projections on the casing which might interfere with the cleaning thereof are obviated and the suspension of the lamp is at the same time rendered very solid.

r , s are flanges; r is situated interiorly on the casing e and s exteriorly on the reflector. The latter flange passes through the flange r when the reflector is accurately centered and prevents its accidental fall by engagement with flange r when the plug f is unscrewed to change the lamp, for the reflector is then no longer held by the engagement of the front ring with the casing e and might fall out if the lamp was held with the glass toward the ground.

The reflector a is prevented from turning in the casing e by the rod t passing through the flange u , which enables the plug to be screwed well home and to bind the reflector in the casing without turning.

Having now particularly described and ascertained the nature of my said invention, and in what manner the same is to be performed, I declare that what I claim, and desire to secure by Letters Patent of the United States, is:

1. An electric lamp for automobiles, comprising a reflector inclosed by a glass in front and terminating at the rear in a screw threaded ring allowing of the introduction of the electric lamp, a casing provided with the necessary means for securing the lantern in position, and a rear plug containing the electric lamp, such plug bearing against a rim of said casing and screwing into the screw threaded ring of the reflector, the whole arranged so that by screwing the plug the reflector will be pressed against the rear part of the casing.

2. An electric lamp for automobiles com-

- prising a reflector having a glass at the front, a casing inclosing the reflector from its front end and spaced therefrom, a plug fitting in the rear end of the casing and in 5 the rear end of the reflector, the plug having co-acting means with the reflector and the casing for drawing the reflector and the casing toward each other, and a lamp arranged in the plug.
- 10 3. An electric lamp for automobiles comprising a reflector having a glass at the front, a casing inclosing the reflector from its front end and spaced therefrom, a plug fitting in the rear end of the casing and in 15 the rear end of the reflector, the plug having co-acting means with the reflector and the casing for drawing the reflector and the casing toward each other, a lamp in the plug, and securing means for the lamp projecting from the plug and attached to the lamp, the securing means being adjustable to change the focal position of the lamp.
4. An electric lamp for automobiles comprising a reflector, a casing surrounding the 25 reflector, the reflector and the casing having co-acting means for limiting the forward movement of the reflector and the rearward movement of the casing, a plug bearing on the casing and on the reflector and having 30 co-acting means with at least one of these elements to force them toward each other to their limit of movement, and a lamp secured in the plug.
5. An electric lamp for automobiles comprising a reflector having a glass in its 35 front, a casing surrounding the reflector and spaced therefrom, the casing and the reflector having means to engage each other to limit their movement toward each other, a plug fitting in the rear of the casing and 40 engaging the reflector to hold the casing and reflector in their positions, a movable back in the reflector, a ring in the plug on which the back slides, a spring bearing on the 45 plug and on the movable back, a ring on the movable back, a lamp so proportioned that it can pass through the back of the reflector when the movable back is removed, and means for securing the lamp in the 50 plug.
6. An electric lamp for automobiles com-
- prising a reflector having a glass in its front, a casing surrounding the reflector and spaced therefrom, the casing and the reflector having means to engage each other 55 to limit their movement toward each other, a plug fitting in the rear of the casing and engaging the reflector to hold the casing and reflector in their positions, a movable back in the reflector, a ring in the plug on 60 which the back slides, a spring bearing on the plug and on the movable back, a ring on the movable back, a lamp so proportioned that it can pass through the back of the reflector when the movable back is removed, 65 a lamp ring to which the lamp is secured, the lamp ring being movable in the ring of the movable back, a tube projecting from the lamp ring through the back of the plug, and means for adjusting the tube forward 70 and rearward in the plug.
7. An electric lamp for automobiles comprising a reflector having a glass in its front, a casing surrounding the reflector and spaced therefrom, the casing and the 75 reflector having means to engage each other to limit their movement toward each other, a plug fitting in the rear of the casing and engaging the reflector to hold the casing and reflector in their positions, a movable 80 back in the reflector, a ring in the plug on which the back slides, a spring bearing on the plug and on the movable back, a ring on the movable back, a lamp so proportioned that it can pass through the back of the 85 reflector when the movable back is removed, a lamp ring to which the lamp is secured, the lamp ring being movable in the ring of the movable back, a tube projecting from the lamp ring through the back of the plug, 90 a spring bearing on the lamp ring and on the plug, and a nut screwing on the tube and bearing on the plug to move the lamp ring against the action of the last-mentioned spring.

In testimony, that I claim the foregoing I have hereunto set my hand this ninth day of December, 1912.

JEAN GALLAY.
